UNITED STATES PATENT OFFICE.

DANIEL MATHIES, OF ROANOKE, INDIANA.

FARM-GATE.

SPECIFICATION forming part of Letters Patent No. 727,661, dated May 12, 1903.

Application filed January 23, 1903. Serial No. 140,201. (No model.)

To all whom it may concern:

Be it known that I, DANIEL MATHIES, a citizen of the United States, residing at Roanoke, in the county of Huntington, in the State of Indiana, have invented certain new and useful Improvements in Farm-Gates; and I do hereby declare that the following is a full, clear, and exact description of the invention, which will enable others skilled in the art to 10 which it appertains to make and use the same, reference being had to the accompanying drawings, which form part of this specification.

My invention relates to improvements in 15 farm-gates.

The object of my present invention is to provide a cheap, simple, efficient, and convenient farm-gate having but few operative parts and provided with an improved means for 20 temporarily supporting it in any desired vertical adjustment for the purpose described.

The principal novel feature of my invention resides in the means for temporarily suspending the gate-body in various vertical adjust- 25 ments.

Similar reference-numerals indicate like parts in the several views of the drawings, in which—

Figure 1 is a view in elevation of my invention looking upon its inner or rear side and showing the relative arrangement of the operative parts. Fig. 2 is a cross-section of the same, taken on the line $x-x$ of Fig. 1. Fig. 3 is a perspective detail of the means for locking the gate-body in its vertical adjustment. Fig. 4 is an end view of the gate when closed, showing the relative arrangement of the gravity-latch. Fig. 5 is a front view of the rear end of the gate, broken away in part and 40 showing the means for securing the same in its closed position.

The upright triangular hanger, upon which the gate-body is suspended, consists of a vertical post 1, a horizontal top piece 2, and an 45 oblique brace 3, whose upper end is fixed in or to the piece 2 near its free end and its lower end to the lower end of the post 1, Fig. 1. The strength and rigidity of the hanger is further increased by means of the metallic 50 stay-rod 4, which rigidly connects the upper end of the post 1 with the forward end of the piece 2, which has proper pintles 5 upon its

extremities. The hanger thus constructed is pivotally supported in the steps 6, fixed in the ground-post 7.

55

The gate-body is preferably constructed in the usual manner of a plurality of horizontal rails 8 and vertical connecting bars or strips 9.

The gate-body is provided approximately midway of its ends with a vertical rod 10, whose ends are angularly bent and passed through the oppositely-arranged central bars 9 and also through the rails 8 and then rigidly secured by proper nuts 11, Fig. 2. The rod 10 also passes loosely through a vertical 60 slot 12 in the forward extended end of the piece 2 of the hanger-frame. On the hanger is loosely arranged a metal plate 13, having a vertical perforation 14 in one end thereof, adapted to loosely admit the rod 10, and having upon its other and forward end a down-turned substantially right-angular flange 15, whose lower edge is centrally recessed to embrace the upper face of the hanger, as shown, to prevent lateral displacement thereof in use. 75

The latch-post 19 for the forward end of the gate has a proper gravity-latch 16, adapted to holdingly engage the adjacent end of one of the rails 8, as shown in Fig. 4, which also rests upon a proper supporting-lug 17 to afford the forward end of the gate sufficient 80 rigidity when at rest.

A staple 18, Fig. 5, is rigidly fixed in the outer face of the post 1 and is adapted to secure the rear end of the gate-body against 85 lateral displacement when closed and also to secure it firmly to the hanger for ordinary use.

The operation and manner of employing my improved gate thus described is obvious and briefly stated as follows: The gate-body 90 and supporting-hanger are swung together, as usual in ordinary use, being firmly secured together by the staple 18. When it is desired to swing the gate over and clear of snow-drifts or other obstructions, the operator releases the ends of the gate-body from their engagement with the latch 16 in the usual manner and from the staple 18 by sliding the gate-body forward sufficiently to become disengaged therefrom, the slot 12 in the hanger 95 permitting this horizontal adjustment. By tilting the gate-body slightly to release it from the binding grip of the plate 13 on the rod 10 he can readily elevate it to any desired 100

vertical adjustment, and by permitting the gate-body, of its own weight, to assume its normal horizontal position the binding grip of the plate 13 will firmly support it in such 5 elevated position. As the rod 10 fits the aperture 14 of the plate 13 loosely, it is obvious that the above-described operation can be effected without any derangement of the plate 13. In like manner the gate-body can be 10 temporarily supported in any desired vertical adjustment when it is desired to rigidly support the gate when closed in such a raised position by the locked engagement of the lower rails of the gate-body for the purpose 15 of affording a passage-way for small animals, as in separating stock or other purposes.

Having thus described my invention and the manner of operating the same, what I desire to secure by Letters Patent is—
20 1. In a farm-gate a pivoted hanger-frame having a vertical slot in its free end; a gate-body; a vertical rod fixed at its opposite ends in the gate-body midway of its ends, and passing loosely through the said slot; and a plate 25 or block having a perforation in one end for the said rod, and having a pendent flange

upon its other end adapted to rest loosely upon the hanger, whereby the said plate will holdingly grip the said rod when the gate-body is in its normal position, all substantially as described. 30

2. The combination of a hanger-frame having a vertical slot in its free end as shown; a gate-body suspended from said hanger at the middle of its length; an upright rod having 35 its bent ends fixed in said gate, and arranged loosely in said slot, and also in a perforation in a binding-plate; and a binding-plate apertured as shown, and provided upon one end thereof with a pendent flange adapted to 40 loosely rest upon the hanger and thereby impart to the plate an inclined position, whereby by the gate-body will by gravity impart to the said plate a binding grip upon the said rod.

Signed by me at Roanoke, Huntington 45 county, State of Indiana, the 20th day of January, A. D. 1903.

DANIEL MATHIES.
